(57) **CLAIM**

What is claimed is the ornamental design for a juicer bowl, as shown and described.

DESCRIPTION

FIG. 1 is a perspective view of a juicer bowl, including an outer housing and an inner basket.

FIG. 2 is a side view of the juicer bowl.

FIG. 3 is a top view of the juicer bowl.

FIG. 4 is a bottom view of the juicer bowl.

FIG. 5 is a top view of the outer housing without the inner basket; and,

FIG. 6 is a cross-sectional view of the outer housing, taken across line 6-6 in FIG. 5.

The broken lines are for illustrative purposes and form no part of the claimed design.
